UNITED STATES PATENT OFFICE.

JOSEPH HERITAGE, OF SOMERVILLE, MASSACHUSETTS.

WAGON-JACK.

SPECIFICATION forming part of Letters Patent No. 738,682, dated September 8, 1903.

Application filed April 27, 1903. Serial No. 154,414. (No model.)

To all whom it may concern:

Be it known that I, JOSEPH HERITAGE, a citizen of the United States, and a resident of Somerville, county of Middlesex, State of Massachusetts, have invented an Improvement in Wagon-Jacks, of which the following description, in connection with the accompanying drawings, is a specification, like figures on the drawings representing like parts.

This invention relates to wagon-jacks which are adapted to raise bodily the entire wagon-body. Jacks of this class have heretofore been constructed with a base and top rails which were pivotally connected together by means of links, so that by swinging the links about their pivotal point of connection with the base the top rails could be raised and the wagon-body lifted thereon. With this construction, however, in order to get sufficient vertical movement of the top rails it is necessary to have the links comparatively long, and when they are made in this way the amount of power which can be developed is not sufficient to raise heavy wagon-bodies because of the long lever-arm about which the top rails swing. If the said links are made comparatively short, greater power may be developed; but this is at the expense of the vertical movement of the top rails.

It is the object of my present invention to improve this class of wagon-jacks by so constructing them that a maximum lift can be provided with a minimum expenditure of power. I have accomplished this result by making the links or members which pivotally connect the top rails with the base in the form of joined members, and I provide means whereby the two arms of each link may be independently swung into their elevated position. With this construction the upper members of the links may be first swung or turned about the joints of said jointed members from their inclined or lowered position to their vertical or raised position, and subsequently the lower portions or arms of said members may be similarly swung from the lowered inclined position to their vertical or raised position. With this construction two separate movements are required to completely elevate the top rails; but as during each movement the top rails are swung about

comparatively short lever-arms a much greater weight can be lifted than if the entire movement of the top rails was about a single long lever-arm. The means I have employed for giving these two separate lifting movements to the top rails comprises a double-toggle-lever arrangement, the straightening of the first toggle-lever operating to give the top rails their first movement, and the operation of the second lever operating to give the said rails their final movement.

The details of construction will be more particularly hereinafter described on reference to the accompanying drawings, in which—

Figure 1 is a perspective view of my improved wagon-jack in its lowered position. Fig. 2 is an elevation of the jack in its partially raised position, the completely raised position being shown in the dotted lines; and Fig. 3 is a vertical section on the line *x-x*, Fig. 1, on an enlarged scale.

The base of the jack comprises the two stringers or rails 3, which are suitably connected together at proper intervals by cross-tie members.

5 designates the top rails, which in operation extend underneath the axles of the wagon-body to be lifted and on which said body rests.

Instead of the usual one-piece connecting member or link between the top rails and the base I have provided jointed connecting members, each comprising the two arms 6 and 7, which are pivotally connected together and also pivotally connected to the top and bottom rails, respectively. Any number of such jointed connecting members may be employed, and they may have any suitable arrangement. I prefer, however, to arrange them in pairs, as shown in Fig. 1, and to place one pair at one end of the jack and another pair substantially centrally of the jack. The two pairs of jointed members are connected together by connecting-rods 8, which connect the joint of one member to that of the other. I preferably employ a hinge-rod 9 for each pair of members, said rod extending through both members of each pair and pivotally connecting them together. The connecting-rods 8 can conveniently connect one rod 9 with the other.

If desired, I may provide the cross-bracing

10 to stiffen each pair of connecting members and prevent the jack from racking under heavy loads. This bracing, however, may be omitted without departing from my invention.

5 When the top rails of the jack are lowered, the connecting members are in substantially the position shown in Fig. 1—that is, in an inclined position—and with the two arms 6 and 7 of each member in substantial alinement.

10 From the above description it will be seen that if the arms 6 are first swung about their pivotal rods 9, so as to bring them into a vertical position, and then the arms 7 swung about their pivotal points of connection with

15 the rails 3, so as to bring said arms into a vertical position, the top rails will be elevated to the same extent as if the connecting members were each a single rigid one-piece link; but by dividing the total vertical movement

20 of the top rails into two swinging movements, each about a comparatively short lever-arm, a much greater weight can be lifted with the expenditure of a given power than if the arms 6 and 7 were rigid one with the other. The

25 means I have provided for giving this double swinging movement to the top rails comprises a double toggle-lever, situated, preferably, at one end of the jack. The first toggle-lever comprises the links or arms 14 and the links

30 or arms 15, which are pivotally connected together, as at 16. The arms 14 are pivoted to the top rails, while the arms 15 are extended beyond the pivotal point 16 to form levers or

35 handles 17, by means of which the toggle-joint may be operated. The second toggle-joint comprises the levers 15, above referred to, and the levers 18, said levers being pivotally connected together, as at 19, and the levers 18 being pivoted to the stringers 3 of the

40 base. The levers 18 are preferably extended beyond the pivotal point 19 to form handles or levers 20. The first-described toggle-levers 14 and 15 are connected to the upper rails by a suitable connecting-rod 21, while the second

45 toggle-levers 15 18 are connected to the lower arms 7 of the connecting members by suitable connecting-rod 22. The rod 21 I have herein shown as connected to one of the arms 6, although this might be connected to any point

50 on one of the upper rails 5 with the same results.

The operation of the device will be readily understood from the foregoing. The parts are shown in Fig. 1 in their lowered position.

55 The first swinging movement of the top rails is accomplished by raising the levers 17 from the position shown in Fig. 1 to the full-line position shown in Fig. 2, this operation straightening the toggle-levers 14 15 and

60 through the connecting-rod 21 swinging the top rails about the pivotal rods 9, thus bringing the arms 6 into substantially vertical position. The second elevating movement of the top rails is accomplished by swinging the

65 levers 20 from the full-line position, Figs. 1 and 2, to the dotted-line position. This movement straightens the second toggle-lever 15

18 and through the connection 22 rocks the levers 7 into a substantially vertical position, as shown in dotted lines, Fig. 2.

70 It will be noted that each of the connecting members comprises the two parts 6 and 7, forming, in effect, a toggle-lever, and I preferably so connect and arrange the parts that when the top rails are elevated into dotted-line position the toggle-levers 6 and 7, as well as the double toggle-levers, have been carried slightly by their dead-centers, so that the structure is locked in its raised position and has no tendency to buckle or collapse under 80 the weight it supports.

It will be noted that during the first swinging movement the top rails swing about a frame which comprises the base and the arms 7 and 18, while during the second movement 85 the top rails and the arms 6 and toggle-levers 14 and 15 are substantially rigid and form the frame which is swung about the arms 7.

85 I will preferably provide the base with suitable casters or rollers 30, so that the jack may 90 easily be moved from place to place, as desired.

95 31 designates dogs which serve to lock the jack in any desired position. These dogs are pivoted to the lower stringers, as at 32, and have noses 33, which bite into the floor or ground and lock the jack against movement. The dogs may be released by depressing the cross-bar 34 and elevating their noses from the ground.

100 I prefer to construct the top rails as shown in the drawings—that is, with the offset portion 40, so that one end of the top rails is at a slightly higher level than the other end. This form of top rail nicely accommodates the ordinary wagon, in which the front axle is 105 slightly lower than the rear axle, for by placing the jack beneath the wagon, so that the rear axle is engaged by the elevated portions of the top rails and the front axle by the lowered portions, the wagon-body is placed 110 in a horizontal position.

115 To accommodate those wagons in which front and rear axles are at substantially the same level, I may employ the supplemental support 41, which is removably supported by the top rails and on which the front axles may rest. When this support 41 is employed, the dropped portion of the top rails between said support and the offset accommodates those

120 vehicles, such as hacks, in which a portion of the body stands at a lower level than the hind axle. This dropped part of the top rails, however, could be formed by making two offsets in them, if desired, and, as I believe I am the first to provide a wagon-jack in which 125 the top rails have the central depressions or dropped portion, I do not wish to be limited to the exact construction herein shown. I also believe that I am the first to provide the jointed connection, such as above described, between the top rails and the base, whereby the complete elevation of the top rails is accomplished by two separate swinging movements made about a comparatively

short lever-arm, and therefore while I have herein shown the best form now known to me of embodying my invention I do not wish to be limited in details of construction. Various changes may therefore be made in the construction of the device without departing from the spirit and scope of my invention as expressed in the appended claims.

By the term "wagon" as herein used I intend to include any form of vehicle, such as a wagon, buggy, caravan, hack, &c.

43 designates stops which may be removably applied to the top rails for the purpose of preventing the wagon-body from slipping forward as the jack is raised.

Having fully described my invention, what I claim as new, and desire to secure by Letters Patent, is—

1. In a wagon-jack, a base, top rails, jointed connecting members pivotally connected to the top rails and base respectively, and means to swing the two arms of the jointed members independently, whereby the top rails are given two separate elevating movements.

2. In a wagon-jack, a base, top rails, a series of arms pivoted to the base, a second series of arms each pivoted to the corresponding arm of the first series and also to the top rails, and means to swing each series of arms about their pivots independently, whereby the top rails are given two separate elevating movements.

3. In a wagon-jack, a base, top rails, jointed members hinged to the base and top rails respectively, a double toggle-lever and connections between one of said toggle-levers and the upper rails, and between the other of said toggle-levers and the jointed members, whereby the straightening of the first toggle-lever 40 swings the upper portion of said jointed members into elevated position, and the straight-

ening of said second toggle-lever swings the lower portion into a similar position.

4. In a wagon-jack, a base, top rails, a series of arms pivoted to the base, a second series 45 of arms, the arms of said second series each being pivoted to the corresponding arm of the first series and to the top rails, a lever pivoted to the base, a second lever pivoted to the first lever, a link connecting said second 50 lever to the top rails, and connections between said levers and the arms of the two series, whereby the first lever swings the arms of the second series about their pivots and partially raises the top rails, and the second lever 55 swings the arms of the first series and completely elevates the top rails.

5. In a wagon-jack, a base, top rails, a toggle-lever connecting said top rails and base at one end, a double toggle-lever connecting 60 said top rails and base at the other end, and connecting members between the two joints of the double toggle-lever and the top rails and joint of the single toggle-lever respectively, whereby when one portion of the double 65 toggle-lever is straightened, the top rails are partially elevated, and when the other portion of said double toggle-lever is straightened the rails are completely elevated.

6. In a wagon-jack, a base, top rails, means 70 connecting said base and top rails, whereby the latter may be raised or lowered, casters carried by said base and gravity-dogs also carried by the base and operating to lock the jack in any desired position.

In testimony whereof I have signed my name to this specification in the presence of two subscribing witnesses.

JOSEPH HERITAGE.
